UNITED STATES PATENT OFFICE.

OLIVER D. HOGUE, OF BOSTON, MASSACHUSETTS.

METALLIC PACKING FOR PIPE-JOINTS.

No. 903,188.

Specification of Letters Patent.

Patented Nov. 10, 1908.

Application filed July 31, 1907. Serial No. 386,336.

To all whom it may concern:

Be it known that I, OLIVER D. HOGUE, a citizen of the United States, and resident of Boston, in the county of Suffolk and State 5 of Massachusetts, have invented an Improvement in Metallic Packing for Pipe-Joints, of which the following description, in connection with the accompanying drawings, is a specification, like letters on the drawings 10 representing like parts.

The aim of my invention is to provide a packing which may be conveniently handled, shipped, and stored without detriment, and readily used at any time cold in practically all situations for making a tight pipe 15 joint. To this end I have provided a packing material in the form of lead or usual alloy drawn into the form of a cable or body of indeterminate length having a peripheral surface in the form of a plurality 20 of protuberant portions with intervening groove-like spaces for facilitating the interlocking and nesting together of a plurality of layers of said article when being calked and welded together cold in superimposed 25 position in a pipe-joint. This body has preferably the same external appearance as a rope, and preferably consists of long individual strands, loosely bunched and slightly 30 twisted into a spiral column, bundle, or cable. This spiral body, column or cable can be readily wound into a pipe joint until the proper amount of malleable packing material is in place, and then pressed or pounded 35 solidly together into a homogeneous cold-welded packing mass, tightly closing the joint with practically the same efficiency as if the lead were melted and poured in in the usual manner. The external protuberances 40 and intervening groove-like spaces permit superimposed layers of the joint-metal to nest into each other and interlock sufficiently to hold each other in place so that the hammering or welding pressure of the calking 45 or tamping process cannot cause them to slip or slide on each other as would be the case with a round or smooth surfaced wire, for instance, but brings them forcibly together without sliding movement. In other words, 50 this formation of the cable or column cooperates in effecting actual welding under proper pressure or blows, and this is accomplished with the highest efficiency when that form of my invention is employed in which 55 the said protuberances of the body or cable-like column are formed by separate indi-

vidual strands and said strands are twisted loosely together in spiral fashion like a rope. This packing material can be readily shipped in suitable lengths or coils, and if accidentally a strand or length gets slightly compressed, it can readily be restored to its original loose condition simply by giving the cable a slight reverse turn, thereby untwisting the rope-like bundle of strands. Also, 60 the loose spiral arrangement not only keeps the individual strands laid smoothly and neatly lengthwise of each other at all times, but permits the cable or bundle to bend readily and conform to any required shape, 65 prevents excessive oxidizing, and leaves the ends in such relation as to facilitate overlapping and interlacing or joining the ends in a complete circle when desired under special circumstances. In some instances I introduce a fibrous core or center.

My invention is confined in its use to bell or spigot pipe-joints.

In the drawings, in which I have shown various embodiments of my invention, Figure 1 represents in side elevation the cable or loosely bunched strands in the simplest form of my invention; Fig. 2 is a similar view, showing a more complete embodiment of the invention; Figs. 3 and 4 are similar 80 views showing still further embodiments of the invention; and Fig. 5 is a sectional view of a pipe joint, illustrating the manner of using my packing with a bell or spigot pipe-joint.

In carrying out my invention in its preferred and simplest form, in which the body, cable or column is formed of separate wires or strands twisted together, the individual strands of weldable metal may be produced 95 in any convenient manner, such, for instance, as commonly employed in making wire, lead pipe, or the like, and then the desired plurality of strands 1 are placed in a bunch lengthwise of each other, and slightly twisted to form a cable or bundle 2, as shown in its simplest form in Fig. 1. Still better results are obtained by making each strand 1 of a plurality of smaller wires or filaments 100 3, each strand being loosely twisted, as distinguished from tightly twisted, and then the strands thus built up are loosely twisted into spiral form, as shown in Fig. 2, where the cable consists of five such strands. By 105 a loose twist, I mean that the strands or wires, although twisted together, are separable or still free to untwist, and they remain 110

as individual wires, not welded together, until finally tamped into a joint, by which operation they then become welded together.

In Fig. 3 I have shown the cable as composed of a central fibrous core 4, about which a plurality of layers of wire-like strands 1 are loosely twisted, and in Fig. 4 I have shown said fibrous core as surrounded by five strands, each made of individual loosely 10 twisted wires or threads 3, the same as in Fig. 2. The advantage of using a central core of fibrous material is that it reduces the amount of lead or alloy required for a given joint, and hence materially lessens the cost. 15 The twist or spiral arrangement of all the wires and strands is in the same direction, so as to permit the loosening up at any time of the component parts simply by untwisting the cable 2.

20 In Fig. 5 I have presented the two ends 5, 6 of pipes which are to be joined together. Accordingly, I first wind in at the bottom of the joint one, or perhaps two, layers of cable, as indicated at 7, composed entirely 25 of lead, and then preferably an intermediate series 8 of cable containing the central fibrous filler, as shown in Figs. 3 and 4, and at the outside a few turns 9 of cable composed entirely of lead, as shown in either Figs. 1 and 30 2. Having filled the joint cavity in this way, I ram or weld the successive layers or turns of cable all tightly together, the result being that the joint is solidly and tightly closed. As lead always comes next to lead, 35 and as all the strands are already laid straight along each other, by which I mean that they are nested in direct contact with each other, and parallel to each other throughout the entire joint-cavity, the result 40 is that the pounding or ramming of the packing necessarily makes an absolutely tight joint, welding the contiguous strands into a homogeneous body. In using the fiber filler form of invention, the end of the cable is 45 twisted for a short distance, and the core or filler is cut off back of the end so as to insure a welded and tight joint at the end, and make it impossible for any moisture to creep back through the fibrous filler, and to hermetically seal the fiber so that it cannot deteriorate and thereby render the joint defective. Also a further advantage of having 50 the individual wires of each strand and also the separate strands of the cable, 55 all twisted loosely in the same direction, is that thereby all movement, whether for tightening or for loosening the cable, tends to affect the relative positions of the wires all alike throughout the entire cable and prevents the unintentional formation of kinks or gaps and openings in the cable, especially 60 when tamping it into the joint.

Various expedients have been proposed for making a pipe-joint cold, and some of these 65 employ lead or equivalent alloy, one of these

being disclosed in the patent of Bühl, No. 787,074, which shows what is sometimes called "lead wool", the lead being spun into filaments and interlaced or mixed into a tangled mass, in appearance like the curled hair used by upholsterers, but such an article is incapable of the uses and advantages above set forth in connection with my invention, as it cannot be untangled or loosened when once pressed together, tends quickly to oxidize and lose its efficiency, and cannot be reduced to cable form, whereas my invention provides the lead or cold-moldable metal in a considerable body or mass, which reduces to a minimum the danger of oxidation and yet, because of the uneven peripheral gripping surface, consisting of alternate protuberances and depressions, provides the requisite capacity for interlocking and nesting together of successive layers of the material as they are wound into the joint, so that each protuberance can find its substantially complementary cavity to nest in and to hold it against slipping or sliding when the tamping pressure is applied, and, furthermore, in its most complete and preferred embodiment, my invention provides not only individual strands laid parallel against each other, but a twisted loose bundle which may readily be untwisted for further loosening the strands or for lapping or interlocking the opposite ends, or to permit the cutting back of the fibrous filler as explained, and the packing is readily and conveniently manufactured, handled, packed, and manipulated.

Having described my invention, what I claim as new, and desire to secure by Letters Patent, is:

1. The herein described article of manufacture, comprising a relatively slender body of indeterminate length composed of cold-weldable joint-metal, said body having a peripheral surface in the form of a plurality of protuberant portions maintained in even, predetermined, uniform shape and relation to each other, with intervening groove-like spaces for facilitating the interlocking and nesting together of a plurality of layers of said article when being calked and welded together cold in superimposed position in a pipe-joint.

2. The herein described article of manufacture, comprising a relatively slender body of indeterminate length composed of cold-weldable joint-metal, said body having a peripheral surface in the form of a plurality of parallel spiral protuberant portions with intervening parallel spiral groove-like spaces for facilitating the interlocking and nesting together of a plurality of layers of said article when being calked and welded together cold in superimposed position in a pipe-joint.

3. As an article of manufacture, a metallic

packing for pipe joints, consisting of a plurality of individual strands of weldable joint-metal capable of being welded together cold loosely assembled in cable form.

5 4. As an article of manufacture, a metallic packing for pipe joints, consisting of a plurality of individual strands of cold-weldable joint-metal loosely twisted into cable form, each strand being itself composed of a plurality of individual wires laid and maintained parallel by a loose twist.

10 5. As an article of manufacture, a metallic packing for pipe joints, consisting of a plurality of individual strands of cold-weldable joint-metal loosely twisted into cable form, each strand being itself composed of a plurality of individual wires laid and maintained parallel by a loose twist in the same direction as the twist of the cable.

15 6. As an article of manufacture, a metallic packing for pipe joints, consisting of a plu-

rality of normally independent, separate individual strands of weldable joint-metal capable of being welded solidly together cold loosely twisted into cable form about a 25 central fibrous filler.

7. As an article of manufacture, a metallic packing for pipe joints, consisting of a plurality of individual strands of cold-weldable joint-metal loosely twisted into cable form 30 about a central fibrous filler, each strand being itself composed of a plurality of individual wires held parallel by being loosely twisted together.

In testimony whereof, I have signed my name to this specification, in the presence of two subscribing witnesses.

OLIVER D. HOGUE.
